F. J. SHUSTER

HEAD PROTECTOR

Filed Oct. 26, 1921

UNITED STATES PATENT OFFICE.

FREDRICK J. SHUSTER, OF CLIFTON STATION, VIRGINIA.

HEAD PROTECTOR.

Application filed October 26, 1921. Serial No. 510,639.

To all whom it may concern:

Be it known that I, FREDRICK J. SHUSTER, a citizen of the United States, residing at Clifton Station, in the county of Fairfax 5 and State of Virginia, have invented certain new and useful Improvements in a Head Protector; and I do hereby declare the following to be a full, clear, and exact description of the invention, such as will enable 10 others skilled in the art to which it appertains to make and use the same.

The invention relates to protective means for the face and head including a cap and a hood, the latter being removable and comprising 15 a transparent plate covering an opening formed in the front of the hood opposite the face.

One of the main features of the invention is the detachable connection of the protector with the cap or head covering whereby to admit of the cap being worn independently of the protector when it is desired to dispense with the latter on warm days.

Other objects and advantages will be apparent and suggest themselves as the nature of the invention is understood.

While the drawing illustrates an embodiment of the invention it is to be understood that in adapting the same to meet different 30 conditions and requirements, various changes in the form, proportion and minor details of construction may be resorted to without departing from the nature of the invention.

Referring to the accompanying drawing 35 forming a part of the specification,

Figure 1 is a perspective view of the protector showing the same applied,

Figure 2 is a vertical central section thereof,

Figure 3 is a horizontal section of the front portion of the protector on the line 3—3 of Figure 1,

Figure 4 is a front view of the removable transparent plate covering the openings in 45 the front of the protector, and

Figure 5 is a sectional detail on the line 5—5 of Figure 2.

Corresponding and like parts are referred to in the following description and designated in the several views of the drawing by like reference characters.

The protector comprises a cap 1 and a hood 2, the latter flaring slightly at its lower end to conform to the shoulders and upper 55 portion of the body. The cap 1 may be of usual construction and design and includes

a visor 3 which extends forwardly of the hood 2. The cap 1 and hood 2 are detachably connected. The front portion of the hood is cut away to provide an opening 4 which is adapted to be closed by a removable transparent plate 5 of mica, celluloid or the like. The cap and hood may be of any suitable material treated in any manner to render the same water proof. The lower portion of the hood 2 is provided with fastenings 6, such as safety pins, whereby the protector may be secured to the clothing when in position. The fasteners 6 may be of any construction which will admit of 70 the protector being detachably connected to the upper portion of the closing which may be of any nature.

A frame 7 surrounds the opening 4 at the bottom and sides thereof. The frame 7 75 may be of any flexible material and serves to confine the transparent plate 5 when in position. The outer edge of the bottom and side portions of the frame 7 are stitched or otherwise permanently attached to the corresponding parts of the hood 2 bordering upon the opening 4. The bottom and side edge portions of the transparent plate 5 are confined by the frame 7 and are stitched therewith to the hood as indicated most 85 clearly in Figure 5. The upper edge of the plate 5 is reinforced by a wire 8 which is whip stitched thereto. The hood is detachably connected with the cap or other form of head covering and hooks 9 and eyes 10 90 are provided for this purpose. Any suitable fastening means may be provided.

The lower portion of the hood flares as indicated at 11 and partakes of the nature of a skirt to fit over the shoulders, the fastenings 6 securing the protector and cap and providing displacement thereof. The hood is open in the rear and the parts bordering upon the opening are adapted to overlap, as indicated more clearly in Figure 5, and 100 are secured by suitable fastenings 12 such as hooks and eyes.

Having thus described the invention, what I claim is:—

A head protector comprising a cap having a comparatively rigid visor projecting forwardly therefrom, a hood detachably connected to the inner side of the cap and having an opening in its upper front portion, a transparent panel secured at its side and bottom edges to said hood and closing said opening, reinforcing means attached to 110

the upper edge of said panel, fastening means carried by the reinforcing means and adapted to cooperate with fastening means carried by the visor at the under side thereof and forwardly of the cap, whereby the weight of the panel is supported by the visor and the panel is spaced from the face of the wearer, and said hood being provided with fastening means spaced

from its vertical edges whereby the vertical 10 edges of the hood may be secured in overlapping relation.

In testimony whereof I affix my signature in presence of a witness.

FREDRICK J. SHUSTER.

Witness:

BENNETT S. JONES.
